UNITED STATES PATENT OFFICE.

LOUIS K. EASTMAN, OF DETROIT, MICHIGAN.

DEVICE FOR DIVIDING POWDER AND FOR FILLING WRAPPERS WITH THE SAME.

No. 899,211.

Specification of Letters Patent.

Patented Sept. 22, 1908.

Application filed March 26, 1907. Serial No. 364,721.

To all whom it may concern:

Be it known that I, LOUIS K. EASTMAN, a citizen of the United States of America, residing at Detroit, in the county of Wayne 5 and State of Michigan, have invented certain new and useful Improvements in Devices for Dividing Powder and for Filling Wrappers with the Same, of which the following is a specification, reference being had therein to 10 the accompanying drawings.

It is the object of the invention to obtain a device by which a quantity of powdered material may be quickly and accurately divided into any desired number of equal parts.

15 To this end, the invention consists in the construction as hereinafter set forth.

In the drawings,—Figure 1 is a perspective view of the powder-holding trough; Fig. 2 is a cross section; Fig. 3 is a view similar 20 to Fig. 2, showing the partition member in engagement with the trough; Figs. 4, 5 and 6 are respectively a plan, cross section and side elevation of the partition member; Fig. 7 is a perspective view of the paper-holder; Fig. 8 is a cross section illustrating the manner of dividing the powders; Fig. 9 is a view similar to Fig. 3, illustrating a modified construction; Fig. 10 is an elevation of the gate; Figs. 11 and 12 are respectively a cross section and side elevation of the partition member illustrated in Fig. 9; Fig. 13 is a side elevation of the powder-leveling device; Fig. 14 is an end elevation thereof, and Fig. 15 is a 30 front elevation of the device as in the act of 35 discharging.

40 Is a trough, of any suitable construction, adapted for receiving the powder to be divided. To vary the capacity of this trough, it is preferably provided with a longitudinally adjustable gate B, which may be set in different positions, according to the number of powders into which the entire quantity is to be divided. The setting of this partition is facilitated by providing markings on the 45 trough, preferably formed in a flange C thereof.

D is a partition member comprising a series of parallel plates, or partitions, E, shaped to fit within the cross section of the trough. 50 The plates E are preferably secured in fixed relation to each other by attachment to a longitudinally - extending strip F, and, as shown in Fig. 3, the latter is provided with a portion G, which laps over the outer edge 55 of the side wall of the trough. The outer portion of the member D is fashioned to form

discharge chutes H between each pair of partitions, these chutes being preferably con-caved and tapered to a point, as shown.

In the use of the apparatus, the operator 60 first determines the number of powders into which the material is to be divided, and adjusts the gate B correspondingly. The powdered material is then placed in the trough and spread out therein, to be of uniform depth 65 throughout the length. The member D is then placed in engagement with the trough, the inner ends of the partitions E cutting through the powder, and extending down to the bottom of the trough, while the flange G 70 extends over the side of the trough. The operator may then invert the trough, dis- 75 charging the powders separated by the par- titions over their respective chutes H into the papers arranged to receive them. To facilitate the placing of the material in the papers, I preferably employ a paper holder, such as I, consisting of a member having a series of vertically-extending plates, or par- 80 titions, spaced correspondingly to the space of the partitions E. The powder-receiving papers are folded and placed between the partitions of the member I, as illustrated in Figs. 7 and 8. Thus, when the trough is in- 85 verted, the discharge chute 8 will register with the spaces between the different papers, and the divided powders may be easily dis- charged into their respective papers. To further facilitate a transfer of the divided powders in the wrappers, I preferably con- 90 struct the rack or holder I with a pair of standards J at opposite ends thereof, and provide the trough A with a pair of trun- 95 nions K, which may be engaged with notches L in said standards. When thus engaged, the trough may be rotated upon the trun- nions so as to discharge the divided powders into the separate wrappers, the chutes being held in perfect registration with their re- 100 spective wrappers.

To secure an accurate division of the powder, it is necessary to distribute it in the trough so as to be of uniform depth through- 105 out, the depth varying according to the bulk of the entire mass. This distribution may be readily effected by means of a leveler M, illustrated in Figs. 13 and 14, which com- 110 prises a shank N carrying at its lower end a scraper O, this being preferably formed of a pair of notched plates conforming to the gen- eral shape of the bottom of the trough. The shank N also adjustably engages a cross-

head P, adapted to slidably engage the upper edges of the trough. In use, the operator may adjust the shank N, and by then moving the cross-head P back and forth the powder will be distributed by the blades O until a uniform level is obtained.

The end gate B may be of any suitable construction, but, as illustrated, consists of a block B', surrounded by a facing B² of rubber or other elastic material, having sufficient resiliency to hold the gate in any position of adjustment.

In place of providing the flange G overlapping the outer edge of the trough, I may employ the construction illustrated in Figs. 9, 10, 11 and 12, in which the strip B' fits within the trough in close proximity to the inner wall thereof.

What I claim as my invention is,—

20 1. In a powder divider, the combination with a trough, and a series of spaced partitions for dividing the material within said trough, of an adjustable end gate for said trough comprising a block and a resilient facing for contacting with the sides of the trough, for the purpose described.

25 2. A powder divider, comprising a trough, a series of partitions for dividing said trough into separate compartments, and means for holding the wrappers for the divided powders in folded position with their edges spaced correspondingly to the spacing between said partitions.

30 3. A powder divider, comprising a trough, a series of partitions for dividing said trough into separate compartments, and a powder-wrapper holder consisting of a member having a series of parallel partitions between which the folded wrapper may be placed, the spacing of said partitions corresponding with the spacing of the partitions in the trough.

35 4. A powder divider, comprising a trough, a series of partitions for dividing said trough into separate compartments, discharging chutes between adjacent pairs of partitions, and a powder-wrapper holder consisting of a base and a series of vertical-parallel partitions between which the folded wrappers may be placed, said partitions being spaced correspondingly to the partitions in the trough.

40 5. A powder divider comprising a trough, a series of spaced partitions for dividing the material in said trough, forming a series of discharge chutes adapted to concentrate the material in the center of the wrapper.

45 6. A powder divider comprising a holder for the powdered material, a leveling device

comprising a notched blade conforming to the general contour of the bottom of the 60 trough, and a slide with which said blade is adjustably engaged.

65 7. A powder divider comprising a holder for the powdered material and a notched leveling blade.

8. The combination with means for dividing a powder bulk into spaced portions, of means for holding a series of folded sheets as wrappers for the powder in correspondingly spaced relation.

70 9. The combination with means for dividing a powder bulk into spaced portions, of a rack for holding a series of folded sheets as wrappers for the powder in correspondingly spaced relation and with the adjacent sides 75 of said wrappers in proximity to the edges thereof in contact.

10. The combination with means for dividing a powder bulk into spaced portions, of a wrapper-holding rack having a series of parallel partitions between which folded sheets as wrappers for the powder may be placed, for the purpose described.

80 11. The combination with a receptacle for a powder bulk and means for dividing the 85 powder therein into spaced portions, of a rack having a series of parallel and correspondingly spaced partitions between which folded sheets as wrappers for the powder may be placed, trunnions on said receptacle and 90 bearings on said rack with which said trunnions may be removably engaged for rotatively holding said receptacle with the spacing thereof and the rack in registration.

12. A powder divider comprising a trough 95 and a series of spaced partitions for dividing the material in said trough, the upper edges of one side of said partitions being connected so as to form a series of discharge chutes.

13. A powder divider comprising a trough 100 and a series of spaced partitions for dividing the material in said trough constituting extensions for one side of said trough whereby a series of discharge chutes is formed.

14. A powder divider comprising a trough, 105 a series of spaced partitions for dividing the material in said trough and a flange between adjacent partitions adapted to fit over the side of the trough and engage one edge thereof.

110 In testimony whereof I affix my signature in presence of two witnesses.

LOUIS K. EASTMAN.
